DRYING APPARATUS.

1,344,241.

Specification of Letters Patent. Patented June 22, 1920.

Application filed March 9, 1918. Serial No. 221,363.

To all whom it may concern:

Be it known that I, SIJTSE HERO MEIHUIZEN, a subject of the Kingdom of the Netherlands, residing at Veendam, Netherlands, Oosterdiep B 35, have invented a new and useful Improvement in or Relating to Drying Apparatus, of which the following is a specification.

This invention relates to a drying apparatus, to be employed for drying amyrum or other materials, for instance for the purpose of determining the amount or quantity of water which they contain. There are drying apparatus known, by which the drying-chamber is provided with a double wall forming a jacket in which a liquid is maintained at boiling point, so that the temperature in the drying-chamber is established in accordance with the boiling point of the liquid. Should a different temperature be required, another liquid can be employed or the pressure exerted on the boiling liquid may be varied, (see Dr. A. Stahler's *Handbuch der Arbeitsmethoden in der anorg. Chemie* 1913, page 472).

It has already been proposed to draw air, which may or may not all be previously dried and heated, through the drying-chamber, and to convey said air by means of natural draft through the drying-chamber to the chimney (Dr. C. Fresenius, *Anleitung zur Quant. Chem. Analyse*, 1903, vol. I, page 56).

Moreover it is known to introduce the material to be dried into the drying-chamber by means of a framework, which can be brought down in the drying-chamber (see German patent No. 55,060).

The apparatus, according to the present invention, consists of two tubes placed one within the other. The inner tube, forming the real drying-chamber, is extended so as to form a chimney, through which the dry air can be drawn from any suitable point by natural draft, and in which at the same time the framework with the materials to be dried can be brought down. The second tube, in which is the boiling liquid, is also extended at its upper end, so that the upper part of the space, formed between both of the said tubes, can be employed as a cooling-chamber for the ascending vapor.

With the extension of the inner tube acting as a chimney above the drying-chamber, the very important advantage is attained, that a good air-circulation is effected by natural draft, no cover is needed and more-

over the framework with the weighing-cups can easily be introduced into and removed from the apparatus.

Further, the present invention relates also to a construction for obtaining a good circulation of the combustion gases from the source of heat necessary for keeping the jacket-liquid boiling. This construction consists in the arrangement of a third tube, surrounding the second tube containing the water or other liquid and extending as far as the cooling-chamber to allow the combustion gases from the source of heat, placed underneath the second tube, to ascend by natural draft through the space thus formed.

To prevent the vapor ascending too rapidly in the cooling chamber, i. e. to insure that no vapor passes the cooling-chamber uncondensed, the latter can be filled up with a packing material, as for instance small pebble-stones.

A very important improvement as regards drying is obtained, according to this invention, by forcing the air to pass along the surface of the materials to be dried. For this purpose a complete disk or plate of small size, is placed immediately under each of the weighing-cups stacked one above the other, a small space being preferably left between the bottom of each cup and its respective disk, as shown in Figure 1, which spaces may be formed by the provision of upwardly extending projections or knobs on the disks. The diameter of these small plates is less than the diameter of the drying-chamber. Above each of the weighing-cups a second plate is arranged, provided in the middle with one or more openings and fitting close to the wall of the drying-chamber, so that the hot air is forced to pass along the surface of the material contained in the cups. This arrangement, for instance, when drying amyrum, prevents the amyrum pasting together and insures the removal or withdrawal of the water in a most complete manner.

Similar reference characters refer to similar parts in each of the several views.

In the accompanying drawings, Fig. 1 is a view showing diagrammatically one form of drying apparatus embodying my invention.

Fig. 2 is a vertical sectional view on an enlarged scale, of the valve shown at the lower left side of Fig. 1, the valve casing being illustrated diagrammatically;

Figs. 3 and 4 are respectively a side and an end view of a clamping pincer adapted for use on the rubber tubes, a fragment of tube being shown in both of the views; and,

5 Fig. 5 is a fragmentary sectional elevation of the lower part of the drying chamber, on an enlarged scale.

The drying-chamber is formed by the lower part of a tube 1, closed at the lower 10 end, and this tube is placed inside a second tube 2, likewise closed at its lower end. Through the wall of the tube 1 close to the bottom passes a tube 3, which also passes through the wall of the tube 2, being her- 15 metically connected to both tubes. To the outside of the wall of the tube 2 a pipe 4 is connected in alinement with the tube 3. This pipe is connected to a vertical tube 5, which at its upper end can be closed by a 20 plug 6, while the lower end of the tube is connected through a mercury seal to one side of a receiver 7 containing concentrated sulfuric acid. At the upper side of the other 25 end of the receiver 7 is connected a tube 8, which as shown in Fig. 2 is formed with a valve casing 8' in which is located a valve 49. The valve 49 consists of a paper disk which in its normal position is supported upon the skeleton frame *a* supported upon a 30 cork ring *b*. Arranged above the valve 49 is another cork ring *b'* which, as shown in Fig. 2, limits the upward movement of the valve. By this arrangement, it will be seen that when the valve is in the raised position, 35 as shown in Fig. 2, the tube 8 is disconnected from atmosphere. The tube 8 can be closed by means of the plug 6 when the latter has been removed from the tube 5.

The tube 2, which is provided with a 40 drain-pipe at its lower end and is partly filled with water, is surrounded by a tubular sheathing 9. This sheathing 9 is closed at bottom by an asbestos card or plate 11, having a hole in the middle under which a 45 spirit-lamp or the like may be placed. This plate rests upon the upper end of a support 10 and bears against the tube 9 as shown in Fig. 1. The space between the tubes 2 and 9, which at the upper side is open, serves as 50 a chimney for the combustion gases of the lamp.

The reason why the asbestos plate is provided with a hole is to prevent too much cold air ascending and also to enable an intimate 55 mixing of the combustion gases with the air to take place, in order to obtain complete combustion.

The part of the space between the tubes 1 and 2, in which the spirit-lamp causes the 60 water to boil, situated above the chimney 9, is made into a cooling-chamber (air-cooler). Furthermore, this part of the jacket may be filled up with packing material 12, for instance pebble-stones, in order to assist the 65 condensation of the liquid vapor. The

jacket-space is closed at the upper end 13, and is there connected with a pipe 14. This pipe 14, which is provided with three branches, having the form of small bends 15, 16, and 17, ends in a downwardly directed 70 bend 18. The small bend 15 is, by means of a rubber tube 19 and a glass tube 20 connected to an air receiver 21 (for example a glass bottle). The bend 16 is in a similar way, by means of a rubber tube 22, a glass 75 tube 23 and another rubber tube 24 connected to an open mercury pressure gage 25, for the constitution of which a Woulff-bottle is illustrated. At the small bend 17 a longer rubber tube 26 is attached to which a glass 80 tube 27 is connected. The bent extremity of the pipe 14 is also by means of a rubber tube 28 connected to a long glass tube 29. The latter has a lower beveled end resting on the bottom of a glass cylinder 30, which is partly 85 filled up with mercury. On the rubber tubes 19, 22, 26 and 28 screw pincers indicated diagrammatically at 31, 32, 33 and 34 are arranged, to allow the rubber tubes to be pinched tightly. The detail construction of 90 the screw pincers is shown in Figs. 3 and 4. This is a common form of pincers and a detail description of the same is thought to be unnecessary.

To force the air, which enters through the 95 tube 3 into the drying-chamber formed by the tube 1, to pass along the heated wall of the latter in order to attain a good heating of this air, a completely closed tank 35, of which the diameter is only a little smaller 100 than the diameter of the tube 1 is brought down as far as the upper side of the tube 3. An enlarged detail view of the tank 35 and adjacent parts are shown in Fig. 5. As will be seen in Fig. 5, the tank 35 is supported 105 by the tube 3 and is secured thereto at 35'. Above this tank a framework 36, suspended on a rope 38 running over two pulleys 37 and loaded with a counterweight 38', is placed in the tube 1, so that the framework 110 can be moved up and down in the tube 1.

In the framework 36 the weighing-cups 39 are stored one above the other, each of them being placed on a solid disk or small plate 40 having a diameter somewhat less than the diameter of the drying-chamber and fixed in the framework. These plates 40 may be provided with upwardly projecting parts or knobs, on which the cups may rest. Above each weighing-cup also another small plate 41 is arranged, which fits tightly against the wall of the drying-chamber and has a hole just above the material contained in the weighing-cups. A similar solid disk or small plate like the small plates 40 is fixed 125 on the upper side of the framework, and provided with a hook, on which the framework is hung. Through this arrangement the weighing-cups are protected at the under side as far as possible against the hot gases, 130

and the air is only allowed to pass above the material to be dried. When passing over the material the hot air absorbs vapor and is cooled. The drying is accelerated through 5 the air passing over the material to be dried, which at the same time prevents any commencement of pasting together of the amy-lum.

On the drawing an apparatus is illustrated such as is employed for operating by 10 a temperature somewhat above 100 degrees C. (for example 105 degrees), as is most usual hitherto.

The mercury receiver 30 is filled up with 15 mercury to a height of 17 cm. (about 6 $\frac{3}{4}$ inch). The screw pincers 31, 32 and 34 are loosened, whereas the screw pincer 33 is screwed up. A moderate flame is placed underneath the apparatus. The water in 20 the tube 2 rapidly commences to boil and vapor arises. This vapor removes the air in the space between the tubes 1 and 2, said air being compressed in the air-receiver 21, the pipe 14 and the Woulff-bottle 25. 25 The mercury in the pressure gage ascends slowly and stops at a certain height, corresponding with the height of the mercury column in the receiver 30. No further increase of the pressure can then take place, 30 because the air would escape by ascending through the mercury in the receiver 30.

After the air beneath the cooling-chamber in the space between the tubes 1 and 2 is entirely removed, *i. e.*, as soon as this space 35 is entirely filled up with vapor, the latter gradually condenses more and more in the cooling-chamber filled with pebble stones 12; consequently the air will not be compressed further, and finally a state of equilibrium 40 will arise, by which the pressure remains constant, and the vapor which is still to be generated, is continually condensed. It is evident that care must be taken that the cooling is so efficient that the generation 45 of vapor does not proceed more quickly than the condensation, which can be easily attained with a sufficient cooling surface, and by preventing the vapor ascending too quickly (by means of the pebble stones) 50 and by a sufficiently moderate heating (a small flame). Since the pressure above atmospheric thus remains constant (17 cm. mercury pressure), the temperature will remain constant in correspondence herewith 55 and established at 105 degrees Celsius.

As shown on the drawing, the tube 1 is comparatively high, so that in this tube, after it has become hot, sufficient natural draft is produced, to provide automatic 60 draft for the air which ascends into the drying-chamber.

The air can as a preliminary be dried or not, but if dried in advance it is passed over the surface of concentrated sulfuric acid 65 contained in the receiver 7. In case such

preliminary drying is required, the tube 5, as shown on the drawing, is closed by the plug 6 and the air is drawn through the open tube 8. If it is desired to operate without preliminary drying, then the plug 6 is 70 simply put on the tube 8 and the air is drawn in such a case through the open tube 5. As represented on the drawing, the air receiver 21 is suspended near the 75 drying apparatus for the purpose of keeping the temperature of said receiver so high, that the air forced therein, is not cooled at all or at least very little to avoid too great a decrease in pressure.

For operating at a temperature of 100 degrees C. (atmospheric pressure) for instance, the glass tube 29 is removed and replaced by a glass tube which is somewhat shorter and only extends to the upper surface of the cylinder 30. For the rest the 80 operation proceeds in the same way as described herein. It can be obtained in a more simple way by opening the screw pincer 33, or uncoupling the tube 14.

Should it be required to operate at a 90 temperature lower than 100 degrees C., for example 65 degrees C., then the glass tube 27 is brought into connection with a suction pump after the screw pincer 33 is opened, (the screw pincers 31 and 34 were already 95 open). Now the air is sucked by means of the pump out of the apparatus, and consequently out of the air-receiver 21, until the mercury in the glass tube 29 reaches a height of about 60 cm. (24 inch) above the mercury in the cylinder 30. The apparatus is supposed to be cold. Now the screw pincer 33 is closed, the suction-pump uncoupled, and afterward the flame placed under the apparatus, which causes the mercury in the 100 tube 29 to descend somewhat. Finally a state of equilibrium is obtained, and the 105 temperature becomes about 65 degrees C. Should the temperature still be somewhat too high, then again more air is sucked out 110 of the apparatus, so that the mercury-column rises further. If the temperature becomes however too low, a little air is admitted to the apparatus by opening the 115 screw pincer 32.

The final case occurs, in which it may be desired to operate at temperatures which correspond with pressures above atmospheric. For a temperature for instance of 125 degrees C. the operation proceeds as follows:

The screw pincer 34 is closed and the pincers 31, 32 and 33 are opened. The glass tube 27 is connected, by means of a rubber tube, provided with a non-return valve (for 125 example a bicycle tire-valve), to an air pump (for example a bicycle pump) and air is pumped into the apparatus, until the mercury in the pressure gage rises to about 60 cm. Now the flame is placed underneath 130

the apparatus, the mercury rises a little further, until the state of equilibrium is established and the gage pressure becomes one atmosphere. Should the temperature be 5 too low, then more air is pumped in; should it be too high, air is let out by opening the pincer 34.

After the samples are entirely dried, the 10 flame is removed and the samples are allowed to cool in the apparatus itself. Here the advantage of the apparatus according to the invention comes to the front, viz. that the apparatus acts as a desiccator. Continually during the cooling as long as the 15 apparatus is still somewhat hot, a little draft will always remain, so that air is still drawn constantly over the concentrated sulfuric acid.

It has been found that no danger exists of 20 the absorption of vapor from air, which after a complete cooling enters at the top into the tube 1, even after several hours. After a couple of hours the apparatus is 25 sufficiently cooled and the weighing of the samples can take place.

This weighing is done as follows:—

In the immediate neighborhood of the tube 1 at the top, the different covers of the 30 weighing-cups are placed one above the other in the same order as the different weighing-cups are placed one above the other.

The framework is now hoisted until the 35 highest weighing-cup just extends above the tube 1, and immediately the first cover is put on this cup. Then the framework is hoisted a little higher and the second weighing-cup is covered and so on, proceeding rapidly until all the samples are covered. 40 Now the uppermost weighing-cup is removed and the framework with the other weighing-cups immediately brought down into the drying-chamber. The highest weighing-cup is now weighed. Then the 45 framework is hoisted again until the second cup can be removed in order to be weighed and immediately the framework with the remaining cups is brought down into the tube again. Every time as the framework 50 is brought down air is drawn at the top into the drying-chamber and inversely a current of air will arise in opposite direction when hoisting the framework. In order to secure the latter, which is an advantage, because 55 the air which is drawn is preliminarily dried by the sulfuric acid, so that every time fresh dry air is brought into the drying-chamber, and to prevent air being drawn in at the top from the possibly humid laboratory room, a

non-return valve is arranged, which in the 60 first case closes and in the second case remains open, as is evident from the drawing.

Having now particularly described and ascertained the nature of my said invention and in what manner the same is to be performed, I declare that what I claim is:—

1. A drying apparatus comprising an open-ended drying-chamber, a jacket surrounding said chamber and adapted to contain water, means for heating the water in 70 said jacket, and means within the jacket for condensing the vapor therein.

2. A drying apparatus comprising an open-ended drying-chamber, a jacket surrounding said chamber and adapted to contain water, means for heating the water in 75 said jacket, means within the jacket for condensing the vapor therein, a frame vertically movable within the chamber, and means for adjustably supporting said frame 80 within the chamber.

3. A drying apparatus comprising a drying-chamber, a heating chamber surrounding a portion of the drying-chamber, a condensing chamber surrounding the remaining 85 portion of the drying-chamber and communicating with the heating chamber, heating means below the heating chamber, and a pipe surrounding the heating chamber and spaced therefrom to provide a chamber for 90 the heating means.

4. A drying apparatus comprising an open-ended drying-chamber, a heating chamber surrounding the drying-chamber, a frame adjustable vertically within a drying-chamber, and trays carried by the frame, 95 said trays being arranged one above the other, and alternate trays being of an area less than the transverse area of the frame, while the remaining trays are formed with 100 central openings.

5. A drying apparatus comprising an open-ended drying-chamber, means for heating and simultaneously creating a draft through the chamber, a frame movable vertically within the drying-chamber, trays carried by the frame, and receptacles supported by certain of the trays, said trays being arranged to direct the draft within 105 the drying-chamber to the top of said receptacles.

In testimony whereof I have signed my name to this specification in the presence of two subscribing witnesses.
